UNITED STATES PATENT OFFICE

LORA E. POOLE, OF ANDERSON, INDIANA, ASSIGNOR TO DELCO-REMY CORPORATION,
OF ANDERSON, INDIANA, A CORPORATION OF DELAWARE

PROCESS AND APPARATUS FOR MAKING ELECTRICAL CONNECTERS

Application filed February 15, 1929. Serial No. 340,077.

This invention relates to the manufacture of flexible connectors, and in particular to the manufacture of flexible connectors for brushes.

It is among the objects of this invention to reduce the cost of making flexible connectors, sometimes called "pig tails", by reducing the amount of labor and the time of making. This is accomplished by providing means for feeding a cable which is to be used in the manufacture of the leads to a station where the pre-formed connector is moved to a position to embrace the cable, then feeding the cable to a station where the clip of the connector is crimped to the cable and finally feeding the cable and the crimped clip to a station where the cable is severed. From this it may readily be seen that the cost of production may be reduced as all that is necessary for the operator to do is to insert a pre-formed clip in the pre-assembly position, from here on all of these steps are pre-formed by a machine.

Further objects and advantages of the present invention will be apparent from the following description, reference being had to the accompanying drawings, wherein a preferred form of the embodiment of the present invention is clearly shown.

In the drawings:

Fig. 1 is a side elevation.

Fig. 2 is a sectional view of the device taken on the line 2—2 of Fig. 1.

Fig. 3 is a sectional view taken along the line 3—3 of Fig. 2.

Fig. 4 is a fragmentary sectional view similar to a portion of Fig. 3, showing the crimping die immediately after performing the crimping operation.

Fig. 5 is a fragmentary view taken on the line 5—5 of Fig. 2, showing the severing device.

Fig. 6 is a sectional view of the intermittent rotating device taken on the line 6—6 of Fig. 2.

Fig. 7 is a detail view of a member of the dial.

Figs. 8 and 9 are detail views of a clamping bolt with an integral arcuate key.

Fig. 10 is a sectional view taken on the line 10—10 of Fig. 7.

Figs. 11 and 12 show the partially formed clip.

Fig. 13 shows the assembled flexible lead. 55

Referring to the drawings, the reference character 20 indicates the base of a press. Bolted to the base 20 is a tool supporting member or base 22. This tool supporting member 22 has mounted thereon a rotary dial 60 mechanism 24 by means of a stud 26 threadedly engaging the member 22. Mounted on the stud 26 is a rotary member 28, as best seen in Fig. 7. This rotary member 28 has a plurality of radially extending slots 30 and 65 triangular projections 32, the purpose of which will appear later.

In each of the radially extending grooves 30 is mounted a forming or crimping die 34 pivotally attached by a pin 40 to a lug 36, 70 which is secured to member 28 by a screw 38. Lug 36 fits snugly between two adjacent triangular projections 32 so as to prevent rotation of member 36 about the screw 38.

In the periphery of member 28 is an annular groove 42 for supporting a cable. Die 34 has a similar, but larger groove 44 aligned with the groove 42 so that substantially a continuous groove extends around the dial. The groove 44 is made large enough to accommodate the clip in addition to the cable, 80 as will appear more clearly later. 75

Concentric with member 28 is mounted an annular member 46 attached to the base 22 by suitable bolts 48. This annular member 85 46 has an inclined surface 50 having substantially the same slant as the inclined surfaces 52 and 53 of members 28 and 34, respectively. Another annular member 54 having a plurality of shouldered recesses 56 is 90 secured to member 28 by a plurality of bolts 58. This annular member 54 limits the rotation of dies 34 about pins 40. 90

A suitable means for intermittently rotating the dial 24 includes a reciprocating member 60 having a dove-tailed groove into which fits the dove-tailed tongue 63 projecting from base 22. Mounted on member 60 by means of a stud 64 is an oscillating arm 62 and a spring 66 biasing arm 62 in a counter-clockwise di- 100

rection as viewed in Fig. 2. On the arm 62 opposite the stud 64 is a pawl 68 which engages the shoulders 70 of the notches 56 in member 54.

5 A suitable driving means for reciprocating member 60 comprises a lug 72 attached to member 60 by a pair of studs 74. Lug 72 is connected to bell crank lever 84 by means of a connecting rod 76 comprising rods 78 and 80 each threadedly engaging member 82, whereby the length of the connecting rod 76 may be adjusted as clearly seen in Figs. 1 and 2. The bell crank being pivotally mounted on the upright 88 as best seen in Fig. 1, by means 10 of a bracket 90 attached to member 88 by a plurality of bolts 92. To the other end of the bell crank lever 84 is pivotally connected by pin 94 to a pitman 96 connected to a crank pin 98 mounted in a radial groove 100 in driving member or wheel 102 mounted upon a drive shaft 104. The eccentricity of pin 98 may be varied by adjusting it in the groove 100. Drive shaft 104 may be driven by suitable means (not shown).

25 It may be readily seen that as the wheel 102 is rotated through one revolution, oscillating motion will be imparted to bell crank 84 which will reciprocate member 60. As member 60 is actuated during the first half-revolution of shaft 104, as viewed in Fig. 1, pawl 68 will be retracted so as to be ready to engage a succeeding notch 56a in member 54, and as member 60 is actuated during the second half-revolution, pawl 68 will be advanced 30 to engage this succeeding notch and rotate the dial 24 in a counterclockwise direction, as viewed in Fig. 2, through a distance equal to the distance between successive notches.

35 It is necessary to apply a braking force 40 upon the dial 24 in order to prevent a clockwise rotation of the dial 24. A leather washer 106 is inserted intermediate member 28 and member 107. Rotation of member 107 is prevented by a key 111 engaging a recess in 45 each of members 28, 106 and 107. From this it may readily be seen that by adjusting the nut 112 the desired friction between members 108 and 28 may be obtained.

50 A crimping device 120 which includes a support 130 is mounted on supporting member 22 by means of a bolt 122 having a square head 124 and an arcuate key 126 integral with the head 124 and the bolt 122. The square head 124 fits into an arcuate groove 55 128 in supporting member 22. The arcuate key 126 prevents the supporting member 130 from rotating about the bolt 122 for the reason that this key 126 engages the sides of the groove 132 in supporting member 22 and it 60 also engages a groove 134 in member 130. Another bolt 136 threadedly engaging the support 22 and extending up through a slot 138 in member 130 cooperates with bolt 122 in holding member 130 in a rigid position on 65 support 22. Member 130 may be adjusted in

a clockwise or a counterclockwise direction with respect to the center of dial 24 so as to properly align a crimping die 140, with the die 34 mounted in groove 30.

70 The crimping die 140 is mounted in a suitable recess 142 in member 130 and held in position by a plate 144 secured to member 130 by bolts 146. The crimping die 140 has a pin 148 fixedly attached thereto extending through a slot 150 in member 144. Another 75 pin 152 is fixedly attached to member 144 so that a tension spring 154 tends to move the crimping tool away from the dial. The crimping die 140 is actuated toward the dial by means of a reciprocating wedge-shaped 80 member 156. This wedge-shaped member is guided in a recess 158 in member 130 a recess 164 in member 130 has been provided for a roller 160 mounted on a pin 162 attached to member 130 in order to reduce the friction 85 between the wall of the recess 158 and member 156.

90 A severing device 170 which includes a support 171, is mounted on supporting member 22. The support 171 is secured to the base 22 by bolts 122a and 138a. The arcuate key 126a integral with the head 124a and bolt 122a prevents rotation of the supporting member 171. Member or support 171 may be adjusted in a clockwise or a counter-clockwise direction with respect to the center of the dial 24 so as to properly align the severing tool 172 with the edge of a groove 95 30 in member 28 so that the knife 172 enters the notch 174 in member 28 and a notch 176 100 in member 46.

105 The severing tool 172 is mounted in a suitable recess 177 in member 171, held in position by a plate 178 secured to member 171 by bolts 180. The severing tool 172 has a pin 182 fixedly attached thereto extending through a slot 184 in plate 178. Another pin 186 is fixedly attached to plate 178 so that a tension spring 188, which has one end attached to pin 182 and the other end attached 110 to pin 186, tends to move the severing tool away from the dial. The severing tool 172 is actuated toward the dial by means of a reciprocating wedge-shaped member 190 extending into the recess 192 in member 171. 115 A recess 194 in member 171 has been provided for a roller 195 mounted on a pin 197 attached to member 171 in order to reduce the friction between the wall of the recess 192 and member 190.

120 The actuating members 156 and 190 are driven by a suitable driving mechanism comprising a reciprocating crosshead 196 into which are fixed securely members 156 and 190. By means of a ball and socket joint 198 125 or any other suitable method, a connecting rod 200 is connected to the crosshead 196. An eccentric cam 202 mounted on the shaft 144 actuates member 200 so that for each revolution of the shaft 104 the crimping die 130

140 and the knife 170 will be advanced toward the dial.

Operation

5 Before starting the device a cable 210, which has a clip crimped upon it near one end, is put into grooves 42 and 44 by the operator so that a crimped clip is in the operating station adjacent the knife. Partially formed clips 212 having substantially the 10 shape of a capital J are hooked on to the cable in the groove adjacent the crimping die 140 and one into each of a couple of preceding grooves as seen in Fig. 2. After the 15 cable, the crimped clip and the three partially formed clips have been placed in this position, the device is ready for operation.

As the driving shaft 104 begins rotating from the position disclosed in Fig. 1, members 156 and 190 will be forced downwardly 20 during the first half revolution of the shaft 104. This will cause the crimping die to be moved toward the dial 24, whereby a groove 141 in the crimping die will engage the J-shaped clip 212 in the preassembled position, forcing this clip around the cable to grip it, as best seen in Fig. 4. At the same 25 time knife 172 will move toward the dial so as to sever the cable adjacent a clip which 30 has already been crimped on to the cable.

As the dimensions of crank arm 84 and the distance of pin 98 from the center of shaft 104 has been so proportioned that pawl 68 moves a substantial distance past the succeeding 35 groove 56, although not far enough to engage a second succeeding groove, shaft 104 is permitted to begin the second half of a revolution from the position in Fig. 1 so as to allow the crimping tool 140 and the 40 knife 172 to be retarded by the springs 154 and 188 to such a distance that the dial will clear the crimping tool and the knife before it begins to rotate. It will thus be seen that the dial will be rotated in a counterclockwise 45 direction during less than the last half of the first revolution.

As the end of the cable 210 and the clip 212 is cut therefrom, the flexible lead and the clip 214 drops into an aperture or opening 209 in supporting member 22 and in the base 20. The annular member 46 has been cut away at 47 so that there will be nothing to support the clip 212 shortly after clip 212 55 has been rotated away from knife 172.

It will be noted that no specific method of pre-forming the clips into the specific shape disclosed, has been described. The manner in which these clips are made is of no importance so far as this invention is concerned, it being only essential that clips of substantially the form claimed be used.

From this it may readily be seen that all the operator is required to do is to insert 60 a partially formed clip 212 into each succeed-

ing groove 30 during the rest period of the dial, at position A for example.

This will reduce the cost of production, as the device will crimp the clip on to a cable and it will cut the cable at the succeeding 70 stage with the clip rigidly attached thereto, thereby speeding up production, reducing the time and reducing the labor so as to produce a cheaper and a better connector.

While the form of embodiment of the present invention as herein disclosed, constitutes a preferred form, it is to be understood that other forms might be adopted, all coming within the scope of the claims which follow,

What is claimed is as follows:

1. A device for producing a flexible electrical connector, comprising in combination, rotary means for intermittently feeding a cable; means for receiving a partially formed clip, said means holding the clip adjacent to 80 the cable; means for crimping the clip to the cable; and means for severing the cable adjacent the crimped clip, thereby forming an electrical connector having a clip attached thereto.

2. A device for producing a flexible electrical connector, comprising in combination, means for receiving and for holding a partially formed clip adjacent to a cable; reciprocating means for crimping the clip to 90 the cable; means for severing the cable adjacent the crimped clip, and means for feeding the cable to each of said means in succession, whereby electrical connectors are formed periodically.

3. A device for producing flexible electrical connectors with a clip attached thereto, comprising in combination, means for intermittently feeding a cable to a plurality of operating stations; means for crimping a clip 100 to the cable at one of said operating stations; and means for severing the cable adjacent the crimped clip at another operating station whereby electrical connectors are produced periodically.

4. A device for producing flexible leads having clips attached thereto, comprising in combination, means intermittently operated for feeding a cable to a plurality of operating positions; means for holding a partially formed clip adjacent to the cable; reciprocating means for crimping the clip during a rest period of the cable feeding means; positive driving means for moving the reciprocating means toward the cable; and resilient 110 means biasing the reciprocating means from the cable.

5. The process of producing a flexible connector comprising the steps of pre-assembling a partially formed clip and a lead, moving the pre-assembled clip and lead to an operating position, crimping the clip at the operating position so as to attach the clip to the lead, moving the lead and the clip attached thereto to another operating position,

severing the cable adjacent to the clip at said other operating position whereby a flexible lead with a clip attached thereto is produced.

6. The process of producing a flexible connector, comprising the steps of feeding a cable to a pre-assembling position; hooking a partially formed J-shaped clip to the cable at the pre-assembling position; feeding the clip and the cable to an operating position; 10 crimping the partially formed clip to the cable at said operating position, and feeding the crimped clip and the cable to another operating station, severing the cable adjacent the clip at said other operating station, thereby producing a flexible lead having a clip attached thereto.

7. The process of producing a flexible connector from a piece of sheet metal and a cable including the steps of forming the piece of 20 sheet metal into a substantially J-shaped clip; hooking the J-shaped clip on the cable; feeding the J-shaped clip and the cable in a pre-assembled relation to an operating station; crimping the clip, while at said operating 25 station, so as to fix it to the cable; and severing the cable adjacent the clip whereby a flexible connector is produced.

8. The process of producing a flexible lead with a clip attached thereto, from a piece of 30 sheet metal and a cable comprising the steps of forming a J-shaped clip from the piece of sheet metal; hooking the J-shaped clip on the cable; moving the J-shaped clip and the cable in a pre-assembled relation to a crimping 35 station; crimping the clip to the cable at the crimping station; moving the crimped clip and the cable to a severing station; and severing the cable adjacent the clip at the severing station so as to produce a flexible 40 lead with a clip attached thereto.

9. The process of producing flexible leads having clips attached thereto comprising the simultaneous steps of hooking a J-shaped clip on a cable; crimping another J-shaped 45 clip to the cable at an operating station; and severing the cable adjacent a crimped clip at a succeeding operation station, so as to sever from the cable a flexible lead having a clip attached thereto.

10. The process of producing flexible leads having clips attached thereto from a J-shaped clip and a continuous cable, comprising a series of cycles of steps, each cycle of steps including; the advancing of the cable with 55 a partially formed J-shaped clip hooked thereon and with a clip previously crimped thereto a distance equal to the length of the flexible lead; then simultaneously hooking a J-shaped clip on the cable, crimping a previously hooked-on J-shaped clip, and severing the cable adjacent a crimped clip whereby a flexible lead with a clip crimped thereto is produced per cycle of steps.

11. An apparatus for making an electrical connector, comprising in combination,

means for feeding a flexible wire, means for fastening a terminal clip to the wire, means for cutting off a piece of the wire with the clip attached, and driving means for driving said clip fastening means and said cutting means, said driving means including a common reciprocating member for actuating the fastening and the cutting means.

12. An apparatus for making electrical connectors, comprising in combination, means 75 for holding a terminal clip against a wire, means for fastening the clip, means for cutting the wire, and means for feeding the wire and the attached clip to the cutting means after the clip has been fastened to the 80 wire.

13. An apparatus for making electrical connectors, comprising in combination, means for receiving and holding a terminal clip against the wire, means for fastening the 85 clip, means for cutting the wire, and means for feeding the unattached clip to the fastening means, and for feeding the wire and the attached clip to the cutting means.

14. An apparatus according to claim 13 in 90 which the feeding means includes a member which engages an attached clip in order to feed the wire to each of said means.

In testimony whereto I hereto affix my signature.

LORA E. POOLE.
